UNITED STATES PATENT OFFICE.

ELBERT C. HOOVER AND IRWIN C. HOOVER, OF WASHINGTON, DISTRICT OF COLUMBIA.

ARTICLE MADE FROM ANIMAL INTESTINES.

Application filed May 27, 1924. Serial No. 716,156.

To all whom it may concern:

Be it known that ELBERT C. HOOVER and IRWIN C. HOOVER, citizens of the United States, residing at Washington, in the District of Columbia, have invented certain new and useful Improvements in Articles Made from Animal Intestines, of which the following is a specification.

Our invention relates to articles made from the gut or intestine of animals, and more particularly to strings or cords made therefrom.

An object of our invention is to make a gut string or cord for use in tennis rackets, music instruments, surgical sutures, looms and the like.

A further object of our invention is to form strings or cords composed of gut, together with other materials, which will be stronger, lighter and less expensively manufactured than has been possible heretofore.

Heretofore it has been customary to use animal intestines for stringing tennis rackets, music instruments, etc. The animal intestines after being suitably treated are twisted together to form a string or cord the number of intestines used being dependent on the size of string or cord desired. After the initial treatment and the twisting together of the intestines to form the string or cord, it is again treated with collodian, varnish or the like with the endeavor of making the twisted structure waterproof.

It has been found, however, that even after waterproofing, moisture will affect the intestines and cause them to break. This is because animal intestines possess very little inherent strength.

It is the purpose of our invention to construct a stranded cord or string, composed of animal intestines or "guts," together with fibrous materials, such as linen, cotton or silk, which will not be affected by moisture and which will be far stronger than strings made from gut alone.

In the accompanying drawings:

Figure 1 illustrates a longitudinal cross section of an animal intestine with a fibrous thread laid loosely therein;

Fig. 2 is a cross section on the line C—C of Fig. 1, showing a plurality of the intestines laid together, with the fibrous threads

therein, prior to twisting them into a unitary structure;

Fig. 3 is a plan view of a section of our improved stranded cord or string after the plurality of intestines with their corresponding threads have been twisted together;

Fig. 4 is a plan view of a modification showing a plurality of split intestines and fibrous threads laid together before twisting them into a cord; and

Fig. 5 is a plan view of the modification of our invention, wherein a number of split intestines A' together with a plurality of fibrous threads B' have been twisted together to form a cord.

Referring to Figs. 1 and 3, it will be noted that the letter A denotes a single intestine and B its corresponding thread. D denotes the stranded structure formed after the required number of intestines A and threads B have been twisted together.

In the process of manufacture, after the intestines A have been cleaned, the fibrous threads B are placed in them by means of a bobbin or other suitable threading means. The threads are preferably composed of silk, but other fibrous materials, such as hemp, cotton or linen, in form of a thread, may be used.

When the intestines have had the fibrous threads placed in them, a suitable number, depending on the size of the cord desired, are twisted tightly together to form a stranded string or cord. The cord is then treated to harden the same and suitably "doped" or waterproofed.

Preferably, though not necessarily, the fibrous threads are loosely placed in the intestines. If the fibrous threads are laid loosely in the intestines before twisting, it has been found that after the complete cord is put into use, as in a tennis racket, and the cord is stretched, the intestines give slightly, but if this stretching is continued the slack in the fibrous threads is taken up and instead of the intestines breaking the threads become taut and relieve the strain on the intestines.

Thus, it will be seen that the addition of the fibrous threads placed in animal intestines when making up a gut string, permits the natural resiliency of the gut to come into

play, but strengthens the intestines and prevents their breaking.

It will be understood that the fibrous threads may be inserted in all or a fraction 5 of the total number of intestines used in making up the stranded cord.

By the use of the intestines together with the fibrous threads, we are able to make up the desired diameter of cord with a less 10 number of intestines than is now required.

In Fig. 4, we have shown a modification of our invention wherein split intestines A', that is, intestines which have been cut longitudinally, are laid together with fibrous 15 threads B', and Fig. 5 illustrates the stranded cord formed after twisting the split intestines A' and B'.

Stranded cords composed of split gut, as customarily made, are stronger than whole 20 gut strings, because they contain a greater number of strands. Whole gut strings, however, are more resilient.

In the preferred embodiment of our invention, we use a plurality of whole intestines with fibrous threads placed in any 25 or all of them and secure the greater resiliency of the whole gut cord with greater strength than the split gut cord by reason of the reinforcing threads.

Another advantage our string possesses 30 is the fact that we are able to turn out a superior product by using salted or otherwise preserved intestines. At present, the best grades of gut strings have to be made 35 from fresh intestines. If intestines which have been kept or preserved any length of time are used, the manufactured strings do not hold up under wear and are noticeably affected by moisture.

We are able to use intestines which have 40 been kept or preserved for some length of time and by reinforcing them, according to our invention, are able to manufacture a

string better than is now produced when the best fresh gut is employed.

What we claim and desire to cover by Letters Patent is:

1. A stranded cord comprising a plurality of animal intestines twisted together, said intestines having threads of fibrous material 50 contained therein.

2. A stranded string comprising a plurality of animal intestines twisted together, said intestines having threads of fibrous material loosely contained therein.

3. A stranded string comprising a plurality of animal intestines twisted together, said intestines having threads of silk passing therethrough.

4. A stranded cord comprising a plurality of animal intestines twisted together, a portion of said intestines having fibrous threads contained therein.

5. A stranded cord comprising a plurality of animal intestines and fibrous threads 65 twisted together.

6. The method of making a stranded cord which consists in inserting a thread of fibrous material within an animal intestine and then twisting several of said threaded 70 intestines into a unitary cord.

7. The method of making a stranded cord which consists in inserting a thread of fibrous material loosely within an animal intestine and then twisting several of said threaded 75 intestines into a unitary cord.

8. The method of making a stranded cord which consists in inserting a thread of silk within an animal intestine, and then twisting several of said threaded intestines into 80 a unitary cord.

In testimony whereof we affix our signatures.

ELBERT C. HOOVER.
IRWIN C. HOOVER.
